FRANK M. LEAVITT, OF SMITHTOWN, NEW YORK, ASSIGNOR TO E. W. BLISS COMPANY, OF BROOKLYN, NEW YORK, A CORPORATION OF WEST VIRGINIA.

GYROSCOPE-SPINNING MECHANISM.

1,291,031.

Specification of Letters Patent. Patented Jan. 14, 1919.

Application filed February 1, 1917. Serial No. 145,854.

To all whom it may concern:

Be it known that I, FRANK M. LEAVITT, a citizen of the United States of America, residing at Smithtown, in the county of Suffolk and State of New York, have invented certain new and useful Improvements in Gyroscope-Spinning Mechanisms, of which the following is a specification.

This invention relates to means for spinning up and releasing a gyroscope, such as are used in the gyroscopic steering mechanisms of automobile torpedoes. The invention is applicable also to other gyroscopic devices.

Heretofore it has been common to provide the gyroscope fly-wheel with a pinion which during spinning is engaged by a meshing pinion on a shaft of the spinning mechanism, which shaft is rapidly revolved by the motive force employed, which in automobile torpedoes is preferably that of compressed air, the shaft in such case carrying a small turbine which receives the impact of the compressed air jets. After a time sufficient for spinning the wheel to the requisite velocity, the driving shaft is displaced so that its pinion is moved out of plane with that on the fly-wheel, and at the same instant the gimbal rings of the gyroscope are set free by withdrawing the locking bolt.

The present invention relates to gyroscopes having spinning devices of the type just described, and its object is to equalize the spinning torque, whereby to protect the pivotal bearings from undue strain and avoid throwing the delicate mechanism out of symmetry.

The invention will be described with reference to the accompanying drawings which illustrate its application to the well-known form of gyroscope used in the steering mechanism of automobile torpedoes.

Figure 1 is a plan of the apparatus partly in horizontal section, on the line 1-1 in Fig. 4;

Fig. 2 is a vertical transverse section on the planes indicated by the lines 2-2 in Fig. 3;

Fig. 3 is a vertical mid-section on the plane of the line 3-3 in Fig. 4;

Fig. 4 is a vertical transverse section on the plane of the line 4-4 in Fig. 3;

Fig. 5 is a fragmentary horizontal section on the plane of the line 5-5 in Fig. 2;

Fig. 6 is a vertical section similar to Fig.

3, but showing the parts after the spinning up and unlocking functions have been performed.

Fig. 7 is a side elevation looking in the contrary direction from Fig. 3, and partly in vertical section, on the line 7-7 in Fig. 5;

Fig. 8 is a diagrammatic view, being a skeleton elevation of the fly-wheel and driving shafts.

Referring to the drawings, A indicates any suitable support or base on which the inclosing shell B of the gyroscope is mounted. The shell B is shown made up of several members, the sole function of this shell being to form a water-tight and substantially air-tight chamber for inclosing the gyroscope proper. C is the gyroscope which comprises the usual fly-wheel a on its spindle b, which is pivotally hung in the normally horizontal inner gimbal ring c, which in turn is pivoted in the outer gimbal ring d, these rings constituting the usual cardan suspension or universal mounting, the outer ring being hung by pivots on a vertical axis in any suitable stationary support, which in this instance is formed by inner projections or pivotal bosses from the shell B. The pivotal bearings are preferably ball bearings, as shown at e and f. The inner ring c is preparatory to and during the spinning, held locked by a bolt g, the end of which enters a socket in the ring (preferably alined with the axis of the fly-wheel), this bolt being withdrawn at the end of the spinning to set the gyroscope free.

The parts thus far described are most commonly provided in gyroscopes for torpedo steering mechanisms. For spinning up the fly-wheel it is commonly provided with a pinion h (preferably duplicated as shown) which is in mesh with a pinion i on a driving shaft D, which shaft passes through a bearing bushing j, passing thereby outside of the shell B and having fixed on its outer end a turbine E. At the instant when the spinning of the gyroscope is required compressed air from any suitable source is admitted to a conduit and emerges through jet orifices, so that it impinges upon the teeth of the turbine and rotates the latter, and thereby revolves the shaft D and through the intermeshing pinions spins up the fly-wheel.

Heretofore there has been provided only one shaft D with its turbine and pinion, the latter consequently engaging the pinion h

2
at only one point and consequently imparting an unbalanced torque to the latter. My invention is based on the conception that this unbalanced torque is a disadvantage in that it 5 throws a side strain on the pivot bearings, and to the extent of the slight play necessarily allowed in ball bearings it throws the fly-wheel axis out of line. By a lateral crowding of the pivotal bearings it generates friction, which 10 it is desirable to avoid. My invention involves the avoidance of this unbalanced thrust by rendering the driving mechanism symmetrical, so that the fly-wheel pinion h will be engaged at two (or more) symmetrically disposed points on opposite sides of its axis of rotation and be subjected to equal and consequently balanced thrusts, whereby 15 it is spun up and its resistance due to its inertia overcome without any lateral crowding of its bearings, and without any consequent generation of frictional retardation, and without any displacement of its normal 20 axis of rotation.

To this end I duplicate (or otherwise 25 multiply) the driving shaft D with its pinion i and turbine E. Preferably I employ two such shafts, the one D being shown as arranged above the fly-wheel axis while its mate D' is placed beneath it. The shaft D' has 30 a pinion i' and a turbine E', which are duplicates of the pinion i and turbine E. The two shafts D D' are carried in parallel sliding bushings j and j' , which are suitably connected together, so that at the moment of 35 unlocking the two bushings move simultaneously and carry the two shafts with them to move the pinions i i' out of mesh with the pinion h .

The invention goes a step further in that 40 it also equalizes the driving torque upon the respective turbines E E'. Instead of driving each turbine by an air jet or jets against one side, it is driven by jets against diametrically opposite sides so that the driving 45 effect is balanced, thereby avoiding any side thrust of the turbine shafts against their bearings and hence causing them to rotate with the nearest approach to ideal absence of friction. This result is accomplished by 50 arranging the air conduits and jets in the manner best shown in Fig. 4, where two conduits k k' are shown, from each of which lead jet orifices l l' which are arranged to direct their jets against diametrically opposite 55 site points on each of the turbines.

In the arrangement shown the compressed air enters through the duct F, whereby it is led to the center of the top side of the shell B, whence it passes through a swivel joint 60 F' into a conduit F² which leads to a valve chamber m in which is a stop valve n , and from the outlet side of this valve two conduits o o' lead to the conduits k k' . The purpose of the swivel joint F' is to permit 65 of the angular displacement of the gyroscope

for what in automobile practice is termed an "angle fire", this, however, being a feature which has no necessary connection with the present invention. The purpose of the valve n is to shut off the compressed air at the 70 end of the spinning operation.

As with prior spinning mechanisms of this character, the construction is such that the spinning operation proceeds for a time sufficient to speed up the fly-wheel to the 75 desired velocity; the time required for this is determined by the operation of a timing mechanism; when the latter is moved through a predetermined cycle corresponding to the time required, it operates the unlocking mechanism. This is ordinarily in the nature of a trip device which is released by the operation of the timing mechanism, and when released causes or permits the 80 unlocking movement. This movement involves 85 essentially the displacement of the pinions i i' to carry them out of mesh with the fly-wheel pinion and out of range of the gyroscope rings; the unlocking of the gyroscope by the withdrawal of the bolt g ; and the 90 shutting off of the compressed air by the closing of the valve n . The unmeshing of the pinions is accomplished by the displacement of the shafts D D', which incidentally displaces the turbines out of the planes of 95 their jets, so that they may cease to be driven even before the closing of the valve n .

These functions are performed in the specific mechanism illustrated, by the means now to be described. One of the shafts D D' 100 (as shown, the shaft D') has a pinion 10 which drives the timing gear or train 11, 12, 13, 14, 15, the latter being a segment best shown in Fig. 7. At the beginning of the 105 operation this segment is in its lowest position; as the spinning proceeds the driving of the train slowly lifts the segment until when it has risen to a predetermined extent (corresponding to the necessary elapsed time) it lifts the pawl p , the lifting of which releases the unlocking mechanism. As 110 shown, this pawl normally engages the angular projection p' of a transverse pivot piece q hung in the lower ends of the long arms of the lever G which is fulcrumed above and has a short arm (shown in Fig. 3) which engages the stem of the valve n and in its normal position holds the valve unseated. The pivot piece q has upright arms r r' (Fig. 2), which engage projections from 115 the sleeves j j' respectively and serve to connect them together. The compressed air pressure against the valve n , which is unbalanced, provides the motive force for operating the unlocking mechanism. The parts are held locked until the pawl p is lifted, as described, whereupon the air pressure causes the parts to move suddenly from the position shown in Fig. 3 to that shown in Fig. 6. This operation thus unmashes the pin- 120

ions, unlocks the gyroscope, and closes the valve n to stop the air flow. The withdrawal of the locking bolt g , which has a tail passing through the pivot piece g (see Fig. 5 6), is accomplished by the pivot piece g striking a collar g' on this tail. There is sufficient lost motion here provided to insure that the pinions shall be displaced in advance of the unlocking, the latter operation 10 not occurring until near the end of the movement.

The timing train 11-14 inclusive is carried by a support s which is fastened to the sleeve j' , so that when the unlocking movement 15 occurs this entire train is moved with the sleeve. The segment 15, however, is pivoted to the fixed support 16, so that the unlocking movement simply carries the terminal pinion 14 away from the segment 15, 20 whereupon the latter drops to its initial position. To restore the parts for another operation consequently it is only necessary to push the displaced shafts D D' back to their original position (having first restored 25 the gyroscope to its normal position), whereupon the pinion 14 will again mesh with the segment 15 and the pawl p will drop into engagement with the locking tooth p' .

The general construction and operation of 30 this timing and unlocking mechanism is similar to those heretofore known, but it presents some differences in specific construction and arrangement which are indicated in the claims.

35 The invention may be varied in construction without departing from its essential features.

I claim as my invention:—

1. The combination with a gyroscope flywheel having a pinion, of a plurality of driving shafts having pinions meshing symmetrically with said pinion whereby to balance the driving torque.
2. The combination with a gyroscope flywheel having a pinion, of a plurality of driving shafts having pinions engaging said pinion on diametrically opposite sides, and

means for imparting an equal rotative effort to the driving shafts.

3. The combination with a gyroscope flywheel having a pinion, of two like driving shafts on opposite sides thereof having pinions engaging said pinion and having fluid pressure turbines for driving them.

4. The combination with a gyroscope flywheel having a pinion, of two driving shafts having pinions engaging with said pinion and having turbines and conduits for conveying fluid under pressure to said turbines, having jet nozzles arranged symmetrically on opposite sides of the respective turbines, whereby to impart a balanced driving effort to said turbines.

5. A gyroscope spinning mechanism comprising twin driving shafts, sliding bearings therefor, a catch normally holding them against displacement, and a timing device adapted to release said catch after a predetermined interval.

6. A gyroscope spinning mechanism comprising twin driving shafts, sliding bearings therefor, a gyroscope lock, a timing mechanism, and a catch normally holding the lock and driving shafts in operative engagement with the gyroscope and to be released by the operation of the timing mechanism.

7. A gyroscope spinning mechanism comprising twin driving shafts, sliding bearings therefor, a gyroscope lock, an air valve, a lever engaging said valve and receiving the stress of air pressure therefrom, a pivot piece hung from said lever and engaging said sliding bearings and lock, and means for releasing said parts at the end of a predetermined movement.

8. A gyroscope spinning mechanism comprising turbine-driven driving shafts, an air valve, an intervening double lever, and a pivot piece hung therefrom and engaging said shafts and lever.

In witness whereof, I have hereunto signed my name.

FRANK M. LEAVITT.
